UNITED STATES PATENT OFFICE.

JULIUS GROB, OF HORGEN, SWITZERLAND, ASSIGNOR TO GROB & CO.,
OF SAME PLACE.

HEDDLE AND HEDDLE-FRAME FOR LOOMS.

SPECIFICATION forming part of Letters Patent No. 489,631, dated January 10, 1893.

Application filed May 28, 1892. Serial No. 434,749. (No model.)

To all whom it may concern:

Be it known that I, JULIUS GROB, of Hor-
gen, canton of Zurich, Switzerland, have in-
vented certain new and useful Improvements
5 in Heddles and Heddle-Frames for Looms, of
which the following is a specification.

The invention consists of an improved heddle
frame or harness in which the heddles are
made of flat metallic blades or bands having
10 their middle parts formed to an eye as it will
be described below, and their ends formed so
as to act as springs against the ends of the
neighbor heddles in view of maintaining the
said heddles to a uniform tautness throughout
15 the length of each bar of the frame.

The invention further concerns a new and
improved disposition of those bars forming
the upper and lower parts of said frame and
of the adjustment of the endrods enframing
20 the heddles to the said bars.

In the accompanying drawings Figure 1 is
a perspective view of a loom harness of my
system in which some parts are broken off to
clearly show the interior devices and in which
25 two different forms of heddles are shown. Fig.
2 shows in side elevation and at an enlarged
scale, how the eyes α are formed in the heddles A.
Fig. 3 is a front elevation of a series
30 of such heddles at the same enlarged scale.
Fig. 4 is a section through the line Y Z of Fig.
3. Fig. 5 shows separately and in perspect-
ive view one of the supports C. Fig. 6 shows
35 another form of the end bars E.

In all the figures the same letters of refer-
ence refer to the same parts.

The heddles A are made of a metallic blade
or band preferably of steel, of suitable length,
having both ends provided with a suitable slit
or mortise α' or α'' to engage the upper and
40 lower cross-rods B which run through all the
heddles of the harness as shown in Fig. 1.
The said ends of the heddles A are moreover
bent either as shown at A' and A'', Fig. 1, or
as shown at A''' and A''', in the said Fig. 1, or in
45 any suitable manner whatever, so as to have
those heddles A bearing with a spring shaped
part of their ends the one against the other,
thus insuring a regular tautness of the heddles
in the harness. The said heddles A are formed
50 at a suitable height, that is to say approxi-
mately at half of their length with an eye α

substantially as shown in Fig. 2. The said eye
 α is a slot of suitable length made in the blade
or band A, and by bending the one half of the
metal α^5 in one direction and the other half 55
 α^6 in the opposite direction, out of the plane
of the band A (see Figs. 2, 3 and 4). The
edges of the eye α are suitably rounded and
smoothed, the thread x passes through the
same as shown in Fig. 2, and will be guided 60
with very little friction and, as it will be seen
by Figs. 3 and 4, the heddles may be drawn
very taut the one to the other without any
interference of the one with the other.

In view of replacing the one or the other of 65
the heddles in the harness without disconnect-
ing the whole device, one may cut the upper
and lower end of such a heddle as shown at α^3
and α^4 in Fig. 1, and by bending somewhat the
whole device such a heddle will easily be 70
removed from the rods B and replaced by a
new one. The rods B are connected to the
hollow bars D, which are made of a slit tube
having suitable embossments or longitudinal
ribs d' , d^2 , d^3 extending throughout their whole 75
length, by means of a suitable number of sup-
ports or bearings C, Fig. 5, formed of two arms
at right angle the one to the other, the one
arm being of suitable breadth to slide within
the embossments (for instance in d^2) and the 80
other arm being provided with a slot c through
which passes the rod B. The slotted arm of
the piece C has a lateral opening so as to be
slipped upon the rod B without withdrawing
the heddles A which might already be thread- 85
ed upon the same. The ends of the hollow
bars D and of the rods B are provided with
corresponding holes H and H' through which
are engaged suitable bolts or screws h.

The endbars E of the harness are provided 90
with suitable lateral projections e^2 which en-
gage one of the ribs, for instance the interior
of the rib d' . The said endbars E are in-
tended to maintain the heddles A at a suit-
able tension upon the rods B and these end 95
bars are provided with two, or more sliding
buckles e e' . When the buckles or bands e
 e' are slid along on the bars E close to the
rods B they will cause the divergence of the
ends of the said bars E and the projections e^2 100
 e^2 of those ends will be pressed thereby firmly
into the interior of the ribs d' , the rod B be-

ing at the same time firmly clasped between the bars E.

To facilitate the lateral spreading of the heddles A, if such spreading is necessary in 5 using the harness, the end bars will preferably be made as shown in Fig. 6, with a chain or other suitable connection E' between the upper and lower bars E².

For the suspension of the heddle-frame in 10 the loom there are provided one or more harness clutches G embracing one or more of the ribs d' d² &c. of the bar D and provided with a sliding buckle or band g by means of which said clutch may be closed or released.

15 The whole device may suitably be plated, tinned or galvanized to be preserved from rust.

Having thus fully described my invention, I claim:

20 1. The heddles A of flat metallic blades formed with mortises and springs near the ends, the springs at the ends of one heddle bearing against the ends of the adjacent heddles, substantially as set forth.

25 2. The combination with the heddles having central eyes, end mortises and springs near the ends, the springs of one heddle bearing against the ends of the adjacent heddle to keep them apart, of bars passing through

30 the mortises of the heddles, the inclosing metallic tubular bars having longitudinal ribs, and angular supports C. mortised for the bars and passing within the longitudinal ribs of the tubular bars, substantially as set forth.

35 3. The combination with the heddles hav-

ing end mortises, and contiguous springs to separate the heddles of bars B passing through the mortises, the end bars E adapted to receive the bars B and the bands e upon the end bars E for clamping the bars B, the 40 inclosing tubular bar D having longitudinal ribs into which the ends of the bars E are received, substantially as set forth.

4. The combination with the heddles having mortises near their ends and contiguous 45 springs, of the bars B passing through the mortises, the supporting pieces C through which the bars B pass, the tubular bars D having longitudinal ribs and receiving within them the ends of the heddles, the bars B and 50 the supports C, the end bars E and their sliding bands e, adapted to pass at opposite sides of the bars B and having outwardly turned ends e² for passing within the longitudinal ribs of the bars D, substantially as set forth. 55

5. The combination with the heddles having central eyes and end mortises and adjacent springs, of the bars B passing through the mortises of the heddles, the inclosing tubular bars D having longitudinal ribs, and the harness clutches G adapted to grasp the ribs of the bars D, substantially as set forth. 60

In testimony whereof I have signed my name to this specification in the presence of two subscribing witnesses.

JULIUS GROB. [L. S.]
